UNITED STATES PATENT OFFICE.

MERTON WEITTENHILLER AND GRANT EDGE, OF PLATTEVILLE, WISCONSIN.

LIFTING DEVICE.

Application filed September 30, 1922. Serial No. 591,478.

To all whom it may concern:

Be it known that we, MERTON WEITTENHILLER and GRANT EDGE, both citizens of the United States and residents of Platteville, in the county of Grant and State of Wisconsin, have invented certain new and useful Improvements in Lifting Devices; and we do hereby declare that the following is a full, clear, and exact description thereof.

10 This invention relates to lifting devices and is particularly directed to a device for lifting and manipulating a barrel.

Objects of the invention are to provide a lifting device particularly adapted to lift barrels, which will lift the barrel from the floor, which will hold the barrel at any desired angle, which may be easily manipulated, which is of extremely simple design, and to provide a barrel lifting device which 20 may be cheaply constructed from standard material.

Although the device is primarily adapted for lifting barrels, it is to be understood that it may be used in other capacities and that 25 the following detailed disclosure is to be construed as illustrative rather than as limiting.

An embodiment of the invention is shown 30 in the accompanying drawing, in which:

35 Figure 1 is a side elevation of the device, showing the barrel in broken lines and illustrating the device in the position it assumes before the barrel is lifted.

Figure 2 is a view corresponding to Figure 1 showing the device after the barrel has been elevated and tilted to the desired angle.

Figure 3 is a plan view of the device, with the barrel removed.

Figure 4 is a detail illustrating the construction of the trunnion bearing.

Referring now more particularly to the drawings, it will be seen that the device comprises a framework composed of two rear legs 1—1, which are suitably braced by 45 diagonally extending bracing rods 2. These rear legs 1 are joined to a similar pair of front legs 3 by a pivotal connection adjacent the upper end of the legs. The front legs are similarly braced by means of 50 diagonally extending bracing rods 4, such rods, in both instances, being of any desired design, such for instance, as the round rods provided with threaded extremities and suitable locking nuts, as illustrated. The rear 55 legs each have a link 5 pivotally joined thereto adjacent their lower ends, as for example,

by means of an extension of the terminal portions of the bracing rods. These links are pivotally joined adjacent their forward edge to the lower portion, or shorter arm, of 60 levers 6, which latter are pivoted to the front legs 3, as for instance, by means of the terminal extensions of the bracing rods 4, such pivot point being indicated at 7 in the 65 drawings.

The barrel receiving or engaging portions 70 comprises a pair of uprights 8 mounted upon each side of the barrel and ending in lower terminal hooks 9 adapted to engage beneath the bottom of the barrel, such barrel being easily tilted to a very slight extent to allow 75 the insertion of the hooks beneath it. A band 10 is provided with an adjustable clamping means, such as tightening screw 11, and is adapted to encircle the barrel and to be clamped in binding relation therewith. One of the uprights 8 is provided with an 80 upper extension 8', which projects beyond the binding strip or band 10, and is provided with a plurality of spaced holes 12.

This barrel supporting structure is pivoted 85 to the upper ends of the forward and rear legs 3 and 1 by means of trunnion bearings, such as is illustrated in Figure 4. These trunnion bearings may comprise a pin having a bearing surface 13 adapted to pivotally receive the front and rear legs and the barrel engaging structure. They are provided also with enlarged heads 14 and threaded 90 reduced extensions 15, such latter portions being screwed rigidly into the clamping band 10, as may be seen from Figure 4.

A latching device in the form of a link 95 16, is pivotally mounted, as indicated at 17, in one of the forward legs 3. It has an angularly projecting extremity 18 adapted to engage any one of the holes 12 in the extension 8' of one of the uprights. In this manner the barrel may be held at any desired angular adjustment, as indicated in Figure 2.

The operation of the device is as follows:— The device is placed over a barrel and the barrel is tilted alternately from one side to the other to allow the insertion of the lifting hooks 9 beneath the lower edge of the barrel. The band 10 is then clamped around the barrel by means of the screw 11, so as to firmly lock the barrel in the barrel engaging portion of the mechanism. The mechanism now occupies the position shown in Figure 1. 110 Thereafter levers 6 are rocked rearwardly, thereby causing their lower portions to draw

the links 5 forwardly. This causes the forward and rear legs to approach each other, thereby lifting the barrel engaging structure upwardly, together with the engaged barrel. 5 The height to which the barrel may be lifted may be determined by the angular setting of the lever 6. It is understood, of course, that, if desired, the levers may be rocked until they occupy a position approximately 10 alining with the links 5. As previously described, the barrel may be tilted to any desired angular position and held in such angular position by means of the latching device and the cooperating holes in the stand- 15 ard.

It will thus be seen that a lifting device has been provided which is eminently suited to handle barrels in an easy and effective manner. It will also be seen that means have 20 been provided upon this lifting device for cooperating with the parts thereof to hold the barrel in any desired position of angular adjustment.

We claim:—

- 25 1. A lifting device comprising a pair of forward and rear legs pivotally joined adjacent their upper ends, lever mechanism connected with the lower portions of the legs and adapted to draw the forward and rear 30 legs towards each other, thereby elevating the pivotal point, and a band pivotally joined to the upper portion of the legs and adapted to be clamped about the object.
- 35 2. A lifting device comprising a pair of forward and rear legs pivotally joined adjacent their upper ends, lever mechanism connected with the lower portions of the legs and adapted to draw the forward and rear legs towards each other, thereby elevating the 40 pivotal point, a band pivotally joined to the upper portion of the legs and adapted to be clamped about the object, and hooks connected with said band and legs and adapted to be positioned beneath such object.
- 45 3. A barrel lifter comprising a band adapted to encircle the barrel, means for clamping the band against the barrel, a supporting framework pivotally joined to said band and including divergent downwardly directed legs, links joined to the rear legs and levers pivoted to the forward legs and to said links whereby when said levers are rocked, said legs are caused to approach each other, thereby raising the barrel.
- 50 55 4. A barrel lifting device comprising a band adapted to encircle the barrel, a pair of uprights extending downwardly from

said barrel and having terminal hooks adapted to be positioned beneath said barrel, a supporting framework including a pair of 60 downwardly divergent legs pivotally joined to said band and uprights adjacent the upper ends of such legs, links pivotally attached to the rear legs, and levers pivotally joined to the forward legs and having their 65 lower ends pivotally joined to said links, whereby when said levers are rocked rearwardly said legs are caused to approach each other, thereby elevating the barrel.

5. A barrel lifting device comprising a 70 band adapted to encircle the barrel, a pair of uprights extending downwardly from said band and having terminal hooks adapted to be positioned beneath said barrel, a supporting framework including a pair of downwardly divergent legs pivotally joined to 75 said band and uprights adjacent the upper ends of such legs, links pivotally attached to the rear legs, levers pivotally joined to the forward legs and having their lower ends 80 pivotally joined to said links, whereby when said levers are rocked rearwardly said legs are caused to approach each other, thereby elevating the barrel, and means for holding the barrel in any desired position of angular 85 adjustment.

6. A barrel lifting device comprising a band adapted to encircle the barrel, a pair of uprights extending downwardly from said band and having terminal hooks adapted to be positioned beneath said barrel, a supporting framework including a pair of downwardly divergent legs pivotally joined to said band and uprights adjacent the upper ends of such legs, links pivotally attached to the rear legs, levers pivotally joined to the forward legs and having their lower ends 90 pivotally joined to said links, whereby when said levers are rocked rearwardly, said legs are caused to approach each other, thereby elevating the barrel, one of said uprights being extended upwardly 95 from said band and provided with a plurality of spaced holes, and a latching device pivotally joined to one of said forward legs and having an angular extension adapted to enter any one of said holes whereby said barrel may be held at any desired angle.

In testimony that we claim the foregoing we have hereunto set our hands at Platteville, in the county of Grant and State of Wisconsin.

MERTON WEITTENHILLER.
GRANT EDGE.
